UNITED STATES PATENT OFFICE.

ADAM WUEST, OF CINCINNATI, OHIO, ASSIGNOR TO ADAM WUEST, A PARTNERSHIP COMPOSED OF ADAM WUEST, ELMER WUEST, AND HERBERT WUEST, OF CINCINNATI, OHIO.

MATTRESS BEATER.

Application filed October 15, 1923. Serial No. 668,588.

To all whom it may concern:

Be it known that I, ADAM WUEST, a citizen of the United States of America, and a resident of Cincinnati, in the county of Hamilton and State of Ohio, have invented a new and useful Improvement in Mattress Beaters, of which the following is a specification.

In the manufacture of mattresses it has heretofore been the custom in smoothing and leveling to beat the surfaces of the mattress with a club to evenly distribute and pack the stuffing material prior to tufting the mattress. This method is slow and very laborious.

An object of my invention is to provide a device for mechanically beating mattresses.

Another object is to provide a device of this kind which is simple of construction.

Another object is to provide a device of this kind that is efficient and rapid in operation.

These and other objects are attained by the means described herein and disclosed in the accompanying drawings, in which:

Fig. 1 is a plan view of a device of my invention.

Fig. 2 is a side elevational view of Fig. 1.

Fig. 3 is a cross sectional elevation on line 3—3 of Fig. 2.

Fig. 4 is a fragmental cross sectional elevation on line 4—4 of Fig. 2.

Fig. 5 is a detail of my invention in perspective.

The machine comprises a rectangular top frame 6, which may be constructed of channel iron and a rectangular base frame 7, secured in spaced relation by uprights 8 at the four corners thereof. Suitable braces 9 may be added to insure rigidity of the framework. Secured to each upright 8 is an upper block 10 and a lower block 11 between which is held a guide rod 12.

Within the frame and between the blocks 10 and 11 is a movable base 13 having secured at its four corners guides 14 through which the guide rods 12 pass and the rods 12 and guides 14 serve to preclude movement of movable base 13 except for vertical reciprocation.

The movable base 13 is capable of adjustment to a raised or lowered position as shown in the left and right portions respectively in Fig. 3. The raising mechanism for moving the movable base 13 comprises a hand

lever 15 for actuating lever shaft 16 which is revolubly mounted in standards 17. Arms 18 are keyed to lever shaft 16 on their one end and carry shaft 19 revolubly mounted in suitable bores in the free ends thereof. Links 20 are pivotally mounted at their opposite ends to shaft 19 and a rod 21 suitably mounted in brackets 210 which are secured to movable base 13.

Midway between the ends of each lever shaft 16 is secured a clevis 22. The clevises 22 extend in substantially opposite directions so that when one extends upwardly the other extends downwardly. A divided tie rod 23 has its ends pivotally mounted on clevis 22 and is connected by a turnbuckle 24 on the threaded ends thereof for adjusting the length of the tie rod, this being a common expedient for that purpose. The arrangement of parts of the raising mechanism is alike at each of the four corners, the clevis 22 being arranged with tie rod 23 to raise or lower each end of the movable base 13 simultaneously. Counterweights 25 are secured to cables 26 which in turn pass over suitable pulleys or rollers 27 and have their ends attached to the movable base 13 to facilitate the raising and lowering operation. While I have shown and described a manually operated lifting mechanism it is understood that any suitable power mechanism could be employed within the scope of the invention.

The paddle or beating mechanism consists of two similar units, the upper one being mounted on the top frame 6 while the lower one is mounted on the movable base 13. Inasmuch as the mechanisms are identical in construction and size except as to the length of the paddle shafts, a description of one will suffice for both.

A series of bearing blocks 28 are mounted on opposite sides of top frame 6. Thru aligned bearing bores in the bearing blocks 28 extend paddle shafts 29 which are square except at the ends where they are turned to fit the bearing bores in the blocks 28. At one side of the shafts 29 are intermeshing paddle shaft gears 30, whereby the successive paddle shafts 29 may be rotated in opposite directions. Mounted on paddle shafts 29 are leather beaters or paddles 31 mounted in spaced relation on the four sides of shaft 29 as shown in Fig. 5. The paddles are so arranged on successive shafts

as to prevent interference of paddles on adjacent shafts. One of the upper shafts 29 has mounted on its one extreme end a suitable pulley 32 which may be connected with a suitable source of power. The same shaft 29 has mounted on its other end a level gear 33. A splined shaft 34 is suitably journaled on top frame 6 and movable base 13. The shaft 34 has a bevel gear 35 keyed thereto at the top to mesh with gear 33. A sliding bevel gear 36 has a key therein engaging in the spline in shaft 34. An intermeshing bevel gear 37 cooperates with sliding bevel gear 36 to transmit power to the lower paddle mechanism which is mounted on movable base 13 in the same manner as the upper paddle mechanism is mounted on top frame 6. Thru the agency of the splined shaft 34 and sliding bevel gear 36 the power may be transmitted to the lower paddle mechanism whether movable base 13 be raised or lowered. The endmost shafts 29 also carry on one end thereof sprockets 38. Cam shafts 39 are retained in a vertical elongated aperture 40 in the hangers 41 secured to upper table 42, and are journaled in suitable bearings 43. Upper cams 44 are keyed to cam shafts 39. A rod 45 extends through suitable bores in the upper part of each pair of hangers 41 and extends beyond said hangers and rests on the cams 44. When the cams are revolved the upper table 42 is raised and permitted to drop abruptly. The aperture 40 in hanger 41 together with cam shaft 39 serves to limit the movement of table 42 to a vertical reciprocation.

The lower table 46 is provided with guides 47 sliding on guide rod 12. As shown in Fig. 4 pins 48 on table 46 ride on the lower cams 49 which are keyed to lower cam shafts 50. The lower cam shafts are journaled in blocks 51 which are supported on movable base 13. The actuating of the cam shafts is accomplished in both upper and lower mechanisms by means of sprockets 38 on the endmost paddle shafts 29 and chain and sprocket connection 51-52 to the several cam shafts. The tables 42 and 46 are not solid but comprise a series of longitudinal slats 53 spaced so that the paddles may pass between them.

In operation a mattress which has been stuffed and bound is placed on lower table 46 mounted on movable base 13 which is then in lowered position as shown in Fig. 2 and in the right half of Fig. 3. The lever 15 is then moved turning lever shaft 16 which swings arms 18 upwardly as shown in left of Fig. 3. The arms 18 carry the shaft 19 with them which pushes upwardly on links 20. This raises the rod 21 carrying brackets 210 which in turn raises the movable base 13. The raising mechanisms 65 at the two ends are actuated simultaneous-

ly through the agency of tie rod 23 and clevis 22 as heretofore explained.

When the table 46 is in this raised position the mattress thereon is brought much closer to table 42 and to the paddles on the upper paddle mechanism.

As previously explained the lower paddle driving mechanism is slidably connected to the splined shaft 34. Power is then applied to pulley 32 whereupon each of the paddle shafts 29 will be revolved, adjacent shafts turning in opposite directions, the paddles 31 rapidly striking the mattress upon the top and bottom. The cams 44 and 49 on the upper and lower mechanisms respectively are at the same time raising the tables 42 and 46 respectively and allowing them to drop abruptly as the shoulders on the periphery of the cams pass the supporting members 45 and 48 of the tables 42 and 46 respectively. Thus the two tables 42 and 46 are oscillated vertically quite rapidly which in practice amounts to a continuous rapid vibration. This vibration permits the mattress to shift about on the table 46 which insures a thorough uniform beating of the mattress over its entire upper and lower sides.

The machine provides a means for rapidly and efficiently accomplishing an operation which has heretofore been slow and very laborious.

A suitable dust collector 54 may withdraw the dust laden air from the device and the mattress thereon, whereby to provide a clean mattress as well as an evenly stuffed mattress.

What I claim is:

1. In a device of the class described the combination with vibrating tables for holding a mattress, of a plurality of paddles for delivering blows to said mattress.

2. In a device of the class described the combination with a pair of vibrating tables between which a mattress may be inserted, the tables having elongated apertures therethrough and a plurality of paddles mounted for rotation and for delivering blows to a mattress through the apertures in the tables.

3. In a device of the class described, the combination comprising a movable base mounted on a frame, means for actuating the movable base, a vibrating table and a beating mechanism carried by the movable base, a second vibrating table and beating mechanism carried by the frame and means for actuating the tables and beating mechanisms.

4. In a device of the class described the combination with a frame of a base movably mounted within the frame, paddle mechanisms mounted on the top of the frame and on the movable base, spaced tables between the paddle mechanisms, cams

for oscillating the tables and means for actuating the paddle mechanisms and the cams.

5. In a device of the class described the combination of a pair of tables having laterally spaced slats, paddle mechanisms having paddles mounted for operation between the slats in the tables, the tables being positioned for receiving a mattress between them, means for actuating the paddles for delivering blows to said mattress and for vibration of the tables.

6. In a device of the class described the combination of a pair of tables having elongated perforations therethrough and mounted for being vibrated, a plurality of paddles mounted adjacent extreme sides of said tables for passing through the perforation in

said tables and means to actuate the paddles and vibrate said tables.

7. In a device of the class described the combination with a framework carrying a movable base mounted for assuming a raised and a lowered position, of paddle mechanisms mounted on the top of the frame and the movable base, cam shafts carrying cams connected with the paddle mechanisms, tables supported by the cams for being rapidly raised and dropped thereby, and means to actuate the paddle mechanisms and the cam shafts.

In testimony whereof, I have hereunto subscribed my name this 3rd day of October, 1923.

ADAM WUEST.
